DESIGN FOR A HOT WATER BOTTLE COVER

Walter H. May, Pelham Manor, N. Y.

Application March 11, 1936, Serial No. 61,561

Term of patent 7 years

To all whom it may concern:

Be it known that I, Walter H. May, a citizen of the United States of America, residing at Pelham Manor, county of Westchester, State of New York, have invented a new, original, and ornamental Design for a Hot Water Bottle Cover, of which the following is a specification, reference being had to the accompanying drawing, forming part thereof:—

Fig. 1 is a front elevational view of a hot water bottle cover showing my new design.

Fig. 2 is a side elevation, and
Fig. 3 is a top plan view.

The characteristic features of my design reside in the configurations of the portions of the hot water bottle cover as shown in solid lines.

What is claimed is:

The ornamental design for a hot water bottle cover, substantially as shown and described.

WALTER H. MAY.
